(57) **CLAIM**

The ornamental design for a vending interface controller, as shown and described.

DESCRIPTION

FIG. 1 is a perspective view from above and in front of the vending interface controller;

FIG. 2 is a perspective view from below and behind the vending interface controller of FIG. 1;

FIG. 3 is a front view of the vending interface controller of FIG. 1;

FIG. 4 is a right side view of the vending interface controller of FIG. 1, the left side being a mirror image thereof;

FIG. 5 is a rear view of the vending interface controller of FIG. 1;

FIG. 6 is a top view of the vending interface controller of FIG. 1; and,

FIG. 7 is a bottom view of the vending interface controller of FIG. 1.

The portions of the vending interface controller shown in broken lines depict environmental subject matter only and form no part of the claimed design.
